UNITED STATES PATENT OFFICE.

HENRY H. CUTLER, OF BROOKLINE, MASSACHUSETTS.

GAS-ENGINE.

1,301,658.

Specification of Letters Patent. Patented Apr. 22, 1919.

Application filed May 18, 1917. Serial No. 169,890.

To all whom it may concern:

Be it known that I, HENRY H. CUTLER, a citizen of the United States, residing at Brookline, in the county of Norfolk and State of Mass., have invented new and useful Improvements in Gas-Engines, of which the following is a full, clear, concise, and exact description, reference being had to the accompanying drawings, forming a part 10 of this specification.

My invention relates to improvements in gas engines, and particularly to means for scavenging the engines. One of the objects of my invention is to provide auxiliary 15 scavenging means independent of the engine shaft for clearing the cylinders of the exhaust products of combustion after an explosion has taken place therein.

Another object of my invention is to provide 20 scavenging means in the form of pistons, said pistons being operated entirely independently of the engine shaft, and the pistons and operating means being constructed in a unit which may be readily substituted for the cylinder head of an ordinary commercial car.

For the purpose of disclosing my invention I have illustrated in the accompanying drawings one embodiment thereof. In said 30 drawings—

Figure 1 is a longitudinal section of a four-cylinder engine embodying my invention;

Fig. 2 is a transverse section taken on the 35 line 2—2 of Fig. 1;

Fig. 3 is a top plan view of the structure illustrated in Fig. 1; and

Fig. 4 is a diagrammatic view illustrating the operation of the invention when used 40 in connection with a six-cylinder engine.

In the embodiment illustrated in Figs. 1 to 3, I have shown a four-cylinder engine, in which the cylinders 1, 2, 3 and 4 may be constructed in the usual manner. I have 45 particularly illustrated in these figures the type of cylinder which is provided with a removable cylinder head and has the valves in the side. These cylinders, as usual, are surrounded by the water jacket 5 and have 50 operating therein, respectively, the pistons 6, 7, 8 and 9. The intake and exhaust valves 10 and 11 of each cylinder are arranged in the side, as is usual in many of the commercial automobile engines.

55 In place of the usual demountable cylin-

der head, I provide a single unit head consisting of a single casting 12 having suitable bolt holes 13 therein through which bolts 14 may be passed to secure the casting directly on the top of the engine cylinder casting. 60 In this single casting 12 there are formed a plurality of cylinders 15, 16, 17 and 18, forming in effect extensions, respectively, of the cylinders 1, 2, 3 and 4; or, in other words, these additional cylinders form compression chambers for each of the cylinders 65 1, 2, 3 and 4.

Operating in the respective cylinders thus formed in the casting 12 are a plurality of pistons 19, 20, 21 and 22. These pistons 70 are connected by suitable connecting rods 23 with cranks 24 on a crank shaft 25 mounted in suitable bearings 26 and 27 formed on the casting 12. The cranks of the pistons 19 and 22 are 180° apart. 75 The cranks of the pistons 20 and 21 are likewise 180° apart, so that the cranks of the pistons 19 and 20 are 90° apart and the cranks of the pistons 21 and 22 are 90° apart. This crank shaft 25 is entirely independent of the crank shaft of the engine and is not connected thereto, the rotation 80 of the crank shaft depending upon the compression and explosion of the charges in the respective cylinders. 85

In operation, we will assume that piston 6 is on the beginning of its power stroke, that is, a charge is compressed in the chamber formed between the piston 6 and the piston 19. The crank on the shaft 25 of 90 the piston 19 is at its uppermost point and therefore on a dead center, with the connecting rod 23 extending in a straight line from the piston 19 to the crank, so that the pressure of the explosive charge on these 95 parts will not tend to rotate the same. With the piston 6 and the piston 19 in this position, the piston 8 of cylinder 3 will be at the end of a power stroke and at the beginning of the exhaust stroke, while the piston 100 21 thereof will be in a half-way position between its extreme up and extreme down position. The piston 7 of cylinder 2 will be at the point of moving upwardly on its compression stroke and the piston 20 105 of the scavenging mechanism will be at a half-way point between its extreme upper and extreme lower movement. The piston 9 of the cylinder 4 will be at the extreme 110 upper end of its exhaust stroke and the

piston 22 will have been moved down to its extreme lowermost position so that these two pistons 22 and 9 will almost meet, there being the very smallest clearance space permissible between these two, so that the volume which can be occupied by the exhaust will be reduced to the minimum.

With the arrangement as above described, the power stroke takes place, driving down the piston 6. At the same time the piston 7 moves up on its compression stroke. The crank connected with piston 19 is on the top dead center, where it remains stationary during the power stroke of the piston 6. At the moment the exhaust valve in cylinder 1 opens the pressure in that cylinder is greatly reduced, and at the same time the compression in cylinder 2 is almost at its maximum, the cylinder 2, it being remembered, being moving on its compression stroke. This compression pressure acting upon piston 20, the crank of which is at right angles to its direction of motion, turns the shaft 25, moving the crank of the piston 19 downwardly and toward the horizontal. At the same time, the crank of the piston 21 is moved from its horizontal to its downward position, thus forcing the piston 21 downwardly to meet the upcoming piston 20, thereby clearing the cylinder 3 of the exhaust gases. At the same time, the crank of piston 22 is moved up to the horizontal, the piston 9 moving down on its intake or admission stroke. While as a matter of fact the compression in cylinder 2 during this operation tends to move the piston 20 upwardly, the upward movement of this piston is really due to the combined effect of the compression and the next explosion stroke, the compression and explosion stroke in a way overlapping to produce the upward movement of the piston. The piston 6 having reached the downward limit of its stroke of course begins on its upward movement on its exhaust stroke. The piston 9 is likewise moving up on its compression stroke, so that the partial rotation of the shaft 5 which was begun by the combined compression and explosive movement of the piston 7 will be completed by the combined compression and explosion taking place in the cylinder 4, and complete the downward movement of the piston 19 so that by the time the piston 19 reaches the lower limit of its stroke the piston 6 will have reached the upper limit of its stroke, the two thus approaching each other and reducing the explosion chamber in the cylinder 1 to the minimum in size, thereby clearing out all of the burned gases and carbon.

The cycle of operation thus described continues in the different cylinders, the shaft 25 being rotated in one direction by the combined compression and explosion of

the charge in two cylinders for the purpose of moving the piston of a third cylinder to the downward limit of its stroke to scavenge the engine. It is apparent that the movement of the shaft 25 is entirely independent, so far as any mechanical connection is concerned, of the engine shaft, and is in no way driven from the engine shaft. 70

In a six-cylinder engine, the construction of the parts is the same as in the four-cylinder engine, except, however, the cranks are differently arranged. 75

In Fig. 4 I have illustrated diagrammatically a six-cylinder engine. This engine, as will be seen, comprises the cylinders 28, 29, 30, 31, 32 and 33, in which operate, respectively, the pistons 34, 35, 36, 37, 38 and 39. 80

The scavenging pistons 40, 41, 42, 43, 44 and 45, respectively, operate in the cylinders 28 to 33, inclusive. These scavenging pistons are connected by pitmen 46 with cranks on the shaft 47. Operating as they do on a six-cylinder engine, the cranks 48, 49, 50, 51, 52 and 53 are disposed at different angles than those of the four-cylinder engine. Cranks 48 and 53 are 180° apart with respect to each other. The same is true of cranks 49 and 52 and 50 and 51. This, however, places cranks 48 and 49 only 60° apart and cranks 49 and 50 60° apart, and so on. 95

In operation, we will assume for purpose of illustration that the piston 34 is just starting on its downward power stroke, that is, an explosion has taken place in the cylinder 28. It will be noted that under these conditions the piston 40 is at the uppermost limit of its stroke and the crank 48 is on its upward dead center. Piston 38 is at the same time moving up on its compression stroke, reaching the limit of its compression stroke, however, before the piston 34 reaches the limit of its explosion stroke, so that, as there is a greater pressure in cylinder 28, under these circumstances, than in cylinder 32, there will be no movement of the crank shaft 47 until an explosion takes place in cylinder 32. 100

However, as soon as the piston 34 reaches the limit of its explosion stroke, the exhaust valves of its cylinder are open and the piston 38 will be moving on its explosion stroke, whereby the pressure in cylinder 28 will have been entirely relieved, and the shaft 47 will be given a partial rotation to move piston 40 down to meet the ascending piston 34, an initial partial rotation to the shaft 47 having been given by the explosion of the charge in cylinder 32, the piston of which has started on its power stroke before the power stroke of piston 34 is completed. As the power of the explosion in cylinder 32 is greater than the partially expanded explosion in cylinder 28, the shaft 47 will rotate even though the exhaust valve in cylinder 110

115

120

125

130

der 28 is not yet opened. The next explosion will take place in cylinder 30, which will likewise give a partial down movement to the piston 40, and this down movement 5 will be completed when the explosion takes place in cylinder 33; so that by the time the piston 34 is moved up to the end of its scavenging stroke the piston 40 will have moved down to meet it until there is the 10 very smallest clearance permissible between these two pistons, as illustrated in cylinder 33, in which the piston 39 is moved up to the completion of its exhaust stroke.

This cycle of operation, with respect to 15 cylinder 1, of course, takes place with each of the cylinders, so that a complete scavenging of each of the cylinders takes place. It will be understood that in this construction I used the same single rotating shaft for 20 operating the scavenging pistons that I did in the four-cylinder engine.

In the four-cylinder engine the movement of the scavenging piston is produced partially by the compression of the charge in 25 the cylinder and partially by the explosion of the charge, while in the six-cylinder engine the entire movement is caused by the explosion of the charge in the cylinders.

Having thus described my invention, what 30 I claim as new and desire to secure by Letters Patent is:

1. In an explosive engine, the combination with a plurality of engine cylinders, each having an explosion chamber therein, 35 of means supplemental to the engine pistons for forcing out of the cylinder the products of combustion after an explosion has taken place, and a rotary shaft operatively independent of the engine shaft for operating 40 said means.

2. In an explosive engine, the combination with a plurality of engine cylinders, each having an explosion chamber therein, of scavenging pistons operating in said 45 chambers, and a rotary shaft operatively independent of the engine shaft for operating said means.

3. In an explosive engine, the combination with a plurality of engine cylinders, 50 each having an explosion chamber therein, of means contracting the volume of said chambers to force the products of combustion out of the same after each explosion, and a rotary shaft operatively independent 55 of the engine shaft operating said means.

4. In an explosive engine, the combination with a plurality of engine cylinders, each having an explosion chamber therein, of auxiliary means mechanically and 60 operatively independent of the engine shaft and operated by the explosion of a charge in the other cylinders for scavenging each cylinder of the products of combustion after an explosion has taken place.

65 5. In an explosive engine, the combina-

tion with a plurality of engine cylinders having their valves in the side thereof, of a cylinder head unit comprising a single casting having a plurality of explosion chambers therein coöperating with said cylinders, scavenging means operating in each of 70 said chambers and a rotary shaft operatively independent of the crank shaft of the engine and mounted on said casting for operating said means.

6. The combination with a plurality of engine cylinders having the valves in the side, of a cylinder head unit arranged to be bodily fastened to said engine cylinders and having a plurality of auxiliary cylinders coöperating with the engine cylinders to form extensions thereof, a plurality of scavenging pistons operating in said auxiliary cylinders and means operatively independent of the engine shaft for operating 85 said pistons.

7. The combination with a plurality of engine cylinders, having the valves in the side, of a cylinder head unit arranged to be bodily fastened to said engine cylinders and 90 having a plurality of auxiliary cylinders coöperating with the engine cylinders to form extensions thereof, a plurality of scavenging pistons operating in said auxiliary cylinders and a rotary shaft operatively independent of the engine shaft for operating 95 said pistons.

8. The combination with a plurality of engine cylinders having the valves in the side, of a cylinder head unit arranged to 100 be bodily fastened to the engine cylinders and comprising a casting having a plurality of auxiliary cylinders formed therein and coöperating with the engine cylinders to form extensions thereof, a plurality of 105 scavenging pistons operating in said auxiliary cylinders, bearings formed on said casting and rotating shaft mounted in said bearings and operatively independent of the engine shaft for operating said scavenging 110 pistons.

9. In a gas engine, the combination with a plurality of engine cylinders, of scavenging means supplemental to the engine pistons for each of said cylinders, and a shaft 115 rotated by the pressure produced in the remaining cylinders for operating the scavenging means of each of said cylinders, said shaft being operatively independent of the engine shaft.

10. In a gas engine, the combination with a plurality of engine cylinders each having an explosion chamber, of scavenging means supplemental to the engine pistons operating in said explosion chambers, a rotating 125 shaft for operating said scavenging means, operatively independent of the engine shaft and rotated by the pressure produced in the engine cylinders.

11. In a gas engine, the combination with 130

a plurality of engine cylinders each having an extension, of scavenging pistons for each of said extensions, and a rotating shaft operatively independent of the engine shaft 5 and rotated by the pressure produced in the engine cylinders and exerted upon said scavenging pistons.

In witness whereof, I have hereunto subscribed my name.

HENRY H. CUTLER.
